CLAIM

The ornamental design for a hat, as shown and described.

DESCRIPTION

FIG. 1 is a perspective view of a hat with the foldable extensions down showing my new design;

FIG. 2 is a perspective view thereof with the foldable extensions up;

FIG. 3 is a left side elevational view of the hat with the foldable extensions down;

FIG. 4 is a right side elevational view thereof;

FIG. 5 is a front elevational view thereof;

FIG. 6 is a rear elevational view thereof;

FIG. 7 is a top plan view; and,

FIG. 8 is a bottom plan view thereof.

The evenly dashed broken lines along the surfaces of the hat depict features of the hat that form no part of the claimed design.

1 Claim, 5 Drawing Sheets
